ARTICLE OF REPOSE FOR SUPPORTING
THE BODY OF A PERSONJohannes Luckhardt, Berlin-Dahlem, Germany,
assignor to Anton Lorenz, Buffalo, N. Y.

Application May 23, 1952, Serial No. 289,497

14 Claims. (Cl. 155—106)

1

The present invention relates to articles of furniture, and more particularly to articles of repose for supporting the body of a person.

An object of the invention is to provide a reclining chair or the like with a link system including a movable back-rest, a movable seat and a movable leg-rest which may be readily and conveniently brought into different positions.

A further object of this invention is to provide a reclining chair or the like which may be readily manufactured at low cost.

Another object of the invention is to improve on the construction of articles of repose for supporting the body of a person as now customarily made.

Other objects and structural details of the invention will be apparent from the following description when read in conjunction with the accompanying drawings forming part of this specification, wherein:

Fig. 1 is a side elevational view of a reclining arm-chair according to the invention, a portion of a side wall of said chair being broken away.

Fig. 2 is a side elevational view of the same chair as shown in Fig. 1, wherein, however, the movable parts of the chair are in a reclined position, and

Figs. 3-6 are diagrammatical illustrations of different embodiments of reclining chairs according to the invention.

Referring now to Figs. 1 and 2, 20 generally indicates the support of an arm-chair comprising side-walls 22—24 connected with each other by cross bars 26. The arm-rests of the chair are included in said side walls.

A back-rest 28 swingably mounted on the support 20 at 30 has a downward extension 32 rigidly connected with the main body of the back-rest. The rear end portion of a seat 34 is swingably mounted on the support 20 at 36.

A leg-rest 38 is swingably mounted at 41 on brackets 40 (only one being shown) rigidly connected with and projecting from the front end portion of the seat 34.

A controlling member, generally indicated by 42, is swingably mounted on the support 20 at 44. According to the embodiment shown in Figs. 1 and 2 said controlling member 42 is in the shape of a cross, wherein the element or intermediate connecting link 46 and the member or guiding link 48 are rigidly connected with each other, for example by welding. The portion or arm 45 of the intermediate connecting link 46 projects from one side of the guiding link 48 and the portion 47 of said intermediate connecting

link 46 projects from the other side of said guiding link 48.

One end of a first connecting link or lower connecting link 50 is pivotally connected at 52 with the controlling member, generally indicated by 42. This pivotal connection 52 is arranged in a plane above the plane of the pivotal connection 44 between the controlling member 42 and the support 20. The other end of said lower connecting link 50 is pivotally connected at 54 with the downward extension 32 of the back-rest 28.

One end of a second connecting link or front connecting link 56 is pivoted to the controlling member, generally indicated by 42, at 58. The other end of said front connecting link 56 is pivoted to the seat 34 at 59.

One end of a controlling link 60 is pivotally connected with the controlling member 42 at 62. The other end of said controlling link 60 is pivoted to the leg-rest 38 at 64.

According to the embodiment shown in Figs. 1 and 2, the pivotal connections 44, 52, 58 and 62 and the controlling member 42 with the support 20, first connecting link 50, second connecting link 56 and controlling link 60, respectively, are spaced from each other.

Furthermore, according to the embodiment shown in Figs. 1 and 2, the pivotal connection 52 is slightly in front of a vertical plane extending through the axis of the pivotal connection 44, when the members of the chair are in the sitting position shown in Fig. 1. The pivotal connections 58 and 62 are located toward the rear in relation to said vertical plane.

Moreover, according to the embodiment shown in Figs. 1 and 2, the pivotal connections 58 and 62 of the controlling member 42 are in planes above the horizontal plane including the pivotal connection 44 of the controlling member 42 with the support 20.

As will be readily understood, the arm chair shown in Figs. 1 and 2 comprises a constrained linkage having stationary link means, i. e. the portions of the support between the pivots 36 and 44 and between the pivots 32 and 44, and having a plurality of movable links, i. e. the downward extension 32 of the back rest 28, the seat 34, the chain of connecting links 50, 46 and 56, and the guiding link 48 rigidly connected with the intermediate connecting link 46 of said chain of connecting links.

A person resting on the chair may readily bring the movable members of the chair from the sitting position shown in Fig. 1 into the reclined

position shown in Fig. 2 by leaning the weight of his body against the back-rest 28. The feature of the arrangement of the pivotal connection 52 between the controlling member 42 and the lower connecting link 50 in or somewhat in front of the vertical plane passing through the pivotal connection 44 (the latter embodiment is shown in the drawings) contributes to an easy displacement of the movable members of the chair from the sitting position of Fig. 1 into the reclined position of Fig. 2. This arrangement renders unnecessary the use of a spring connected with a stationary portion of the support and the controlling member 42 having the tendency of urging said controlling member 42 in clockwise direction as viewed in Fig. 1.

The movable members of the chair may be held in any desired position by means of locking means, not shown.

Furthermore, the extreme sitting and reclining positions of the movable members of the chair may be limited by stops.

The embodiment shown in Fig. 3 substantially corresponds to the embodiment shown in Figs. 1 and 2. However, the controlling member 142, instead of being in the shape of a cross, comprises a guiding link 148 having a first arm 145 and a second arm 147. Both arms are rigidly connected with the guiding link 148. The arm 145 pivoted at 158 with the connecting link 156 projects from one side of the guiding link 148. The arm 147 pivoted at 152 with the connecting link 150 projects from the other side of the guiding link 148. The points of connection of said arms 145 and 147 with the guiding link 148 are offset.

The lower end of the guiding link 148 is pivoted to the support at 144, the upper end of said guiding link 148 is pivoted to the controlling link 160 at 162. The back-rest and the seat are indicated by 128 and 134, respectively. The back-rest 128 is pivoted to the support at 130 and the seat is pivoted to said support at 136. The leg-rest 138 is swingably mounted on the seat 134 at 141.

According to the embodiment shown in Fig. 4 the controlling member 242 pivoted to the support at 244 is in the shape of a bell crank lever having a first arm 245 pivoted at 258 to the connecting link 256 and having a second arm 247 pivoted at 252 to the connecting link 250. The upper end of a bar 248 rigidly connected with the bell crank lever 245, 247 is pivotally connected at 262 with the controlling link 260. The back-rest swingably mounted on the support at 238 is indicated by 228. The seat swingably mounted on the support at 236 is indicated by 234. 238 indicates the leg-rest swingably mounted on the seat 234 at 241.

If desired, the leg-rest 238 shown in Fig. 4 could be omitted. In such a case, of course, the controlling link 260 and the bar 248 would also be omitted.

According to the embodiment shown in Fig. 5 the controlling member 342 is in the shape of a plate. The connecting link 356, the connecting link 350 and the controlling link 360 are pivoted to said plate 342 at spaced points 352, 358 and 362, respectively. The downward extension 332 of the back-rest 328 pivoted to the support at 330 is pivotally connected with the connecting link 350 at 354. The leg-rest 338 is pivotally connected with the controlling link 360 at 364 and with the seat 334 at 341. The rear end portion of the seat 334 is pivoted to the support at 330 at a point in coaxial alignment with the pivotal

connection between the back-rest 328 and the support.

According to the embodiment shown in Fig. 6, again the back-rest 428 and the seat 434 are pivotally connected with the support at a common point 430. One end of the lower connecting link 450 is pivoted to the extension 432 of the back-rest 428 at 454. The other end of said connecting link is pivoted at 452 to the arm 447 of an intermediate connecting link 446 in the shape of an inverted V. The other arm 445 of said intermediate connecting link is pivoted at 458 to one end of the connecting link 456, the other end of which is pivoted to the seat 434 at 459. The intermediate connecting link 446 is rigidly connected with the upper end of the guiding link 448, the lower end of which is pivoted to the support at 444. The upper end of said guiding link 448 is in pivotal connection at 462 with one end of the controlling link 460, the other end of which is pivoted at 464 to a leg-rest 438 swingably mounted on the seat 434 at 441.

Thus, according to the embodiment shown in Fig. 6, the controlling member 442 comprises the guiding link 448 and the intermediate connecting link 446, the arms 445 and 447 of which project downwardly from each side of said guiding link 448.

I have described preferred embodiments of the invention, but it is understood that this disclosure is for the purpose of illustration, and that various omissions or changes in shape, proportion and arrangement of parts, as well as the substitution of equivalent elements for those herein shown and described, may be made without departing from the spirit and scope of the invention, as set forth in the appended claims.

What I claim is:

1. An article of repose for supporting the body of a person, comprising: a support, a back-rest pivotally mounted on said support, said back-rest having a downward extension, a seat, the rear portion of said seat being swingably mounted on said support, a controlling member pivotally connected with said support, a first connecting link, said first connecting link being pivoted at its rear end to said downward extension of the back-rest and at its front end to said controlling member, the pivotal connection of said controlling member with said support being in a plane below the plane of the pivotal connection of said controlling member with said first connecting link, a second connecting link, one end of said second connecting link being pivoted to said controlling member, the other end of said second connecting link being pivoted to said seat, a leg-rest swingably mounted on the front portion of said seat, and a controlling link pivoted at one of its ends to said leg-rest and at its other end to said controlling member.

2. In an article of repose as claimed in claim 1, the pivotal connection between said controlling member and said first connecting link being substantially in the vertical plane through the pivotal connection between the controlling member and the support when the movable members of the article are in the normal sitting position, and the pivotal connections between said controlling member and said second connecting link and said controlling link being located toward the rear in relation to said vertical plane.

3. In an article of repose as claimed in claim 1, the pivotal connection between said controlling member and said controlling link being in a plane

above the plane of the pivotal connection of said controlling member with said support.

4. In an article of repose as claimed in claim 1, the pivotal connections of the controlling member with the first connecting link, the second connecting link and the controlling link being spaced from each other.

5. In an article of repose as claimed in claim 1, said controlling member being in the shape of a cross, the lower end of said cross being pivoted to said support, the upper end of said cross being pivoted to said controlling link, one arm of said cross being pivoted to said first connecting link, and the other arm of said cross being pivoted to said second connecting link.

6. In an article of repose as claimed in claim 1, said controlling member including a link pivoted at its lower end to said support and at its upper end to said controlling link, a first arm rigid with said first mentioned link and projecting from one side thereof, said first arm being pivoted to said first connecting link, and a second arm rigid with said first mentioned link and projecting from the other side thereof, said second arm being pivoted to said second connecting link, and the points of connection between said two arms and said first mentioned link being offset.

7. In an article of repose as claimed in claim 1, said controlling member being in the shape of a bell-crank lever, one arm of said bell-crank lever being pivoted to said first connecting link, the other arm of said bell-crank lever being pivoted to said second connecting link, and a bar rigid with said bell-crank lever at its lower end, said bar being pivotally connected with said controlling link.

8. In an article of repose as claimed in claim 1, said controlling member being in the shape of a plate.

9. In an article of repose as claimed in claim 1, said controlling member comprising a link pivoted at its lower end to said support and at its upper end to said controlling link, a first arm rigid with said first mentioned link and projecting downwardly from the upper end thereof, said first arm being pivoted to said first connecting link, and a second arm rigid with said first mentioned link and projecting downwardly from the upper end thereof, said second arm being pivoted to said second connecting link.

10. An article of repose for supporting the body of a person, comprising: a support, a constrained linkage having stationary link-means and a plurality of movable links, said stationary link-means being included in said support, said movable links including a seat-member, a downward extension of a back-rest member, a guiding link

and a chain of connecting links including a lower connecting link at one end of the chain, a front connecting link at the other end of the chain and an intermediate connecting link pivoted to said lower and front connecting links, said guiding link being rigid with said intermediate connecting link and being pivoted at its lower end to said support, said lower connecting link being pivoted to said downward extension of the back-rest member, said front connecting link being pivoted to the front portion of said seat member, means pivotally connecting at least one of said back-rest- and seat-members with said support, a leg-rest swingably mounted on the front portion of said seat-member, and a controlling link, one end of said controlling link being pivoted to said leg-rest, the other end of said controlling link being pivoted to said guiding link.

11. In an article of repose as claimed in claim 10, said guiding link and said intermediate connecting link being integral with each other.

12. In an article of repose as claimed in claim 10, said guiding link projecting from both sides of said intermediate connecting link.

13. In an article of repose as claimed in claim 10, said intermediate connecting link being in the shape of a V, and being rigidly connected with said guiding link near the upper end of the latter.

14. An article of repose for supporting the body of a person, comprising: a support, a back-rest pivotally mounted on said support, said back-rest having a downward extension, a seat, the rear portion of said seat being swingably mounted on said support, a controlling member in the shape of a bell-crank lever pivotally connected with said support, a first connecting link, said first connecting link being pivoted at its rear end to said downward extension of the back-rest and at its front end to one arm of said bell-crank shaped controlling member, the pivotal connection of said controlling member with said support being in a plane below the plane of the pivotal connection of said arm of the controlling member with said first connecting link, and a second connecting link, one end of said second connecting link being pivoted to the other arm of said bell-crank shaped controlling member, the other end of said second connecting link being pivoted to said seat.

JOHANNES LUCKHARDT.
